(57) CLAIM

We claim the ornamental design for a toothbrush having tongue cleaner, as shown and described.

DESCRIPTION

FIG. 1 is a back perspective view of the toothbrush having tongue cleaner;

FIG. 2 is a front elevation view of the toothbrush having tongue cleaner;

FIG. 3 is a back elevation view of the toothbrush having tongue cleaner;

FIG. 4 is a left side elevation view of the toothbrush having tongue cleaner;

FIG. 5 is a right side elevation view of the toothbrush having tongue cleaner;

FIG. 6 is a top plan view of the toothbrush having tongue cleaner; and,

FIG. 7 is a bottom plan view of the toothbrush having tongue cleaner.

The broken lines shown in the drawings illustrate features of the article in which the design is embodied that form no part of the claim.
